UNITED STATES PATENT OFFICE.

OTTO LE GRAND DILWORTH, OF HARTFORD, CONNECTICUT.

ARTIFICIAL ARM AND HAND.

1,385,817.

Specification of Letters Patent. Patented July 26, 1921.

Application filed March 23, 1917. Serial No. 157,032.

To all whom it may concern:

Be it known that I, OTTO LE GRAND DILWORTH, a citizen of the United States, residing at Hartford, in the county of Hartford and State of Connecticut, have invented a new and Improved Artificial Arm and Hand, of which the following is a specification.

My invention relates to the class of devices above named and an object of my invention, among others, is to provide an artificial arm and hand that may be readily operated and that shall have a maximum number of the movements of a natural hand and arm, and which movements shall closely imitate those of natural members.

One form of device embodying my invention and in the construction and use of which the objects herein set out, as well as others, may be attained, is illustrated in the accompanying drawings, in which:

Figure 1 is a picture of a man showing my improved artificial arm and hand attached to a stump of his natural upper arm member.

Fig. 2 is a view of my improved hand and arm looking at the outer side.

Fig. 3 is a similar view looking at the inner side of the arm and hand.

Fig. 4 is a view, scale enlarged, of my improved hand and arm with parts broken away to show construction, the forearm being bent upwardly and the hand being turned to a different position from that shown in Figs. 1 to 3.

Fig. 5 is a view similar to Fig. 4, but looking, however, toward the back of the hand.

Fig. 6 is a detail view, scale enlarged, of the finger mechanism with parts broken away to show construction.

Fig. 7 is a detail view through the parts shown in Fig. 6 on a plane denoted by dotted line 7-7 of Fig. 6.

Fig. 8 is a detail view, scale enlarged, illustrating the mechanism for producing the wrist movement.

Fig. 9 is a view, looking from the right, of the parts shown in Fig. 8, the cover within the socket being removed.

In the accompanying drawings the numeral 10 denotes a vest to be worn by a person, and which closely fits the body and affords a means for anchorage of different parts employed in manipulating my improved hand and arm. These members are

attached to the vest in a manner to be hereinafter described.

The numeral 11 indicates the upper arm and 12 the forearm of my improved device, the former being hollow, thus providing a recess to receive the stump 13 of the natural arm. A saddle 14 rests on the shoulder of the person and has straps 15, 16 attached to the saddle and the upper arm and to the saddle and the vest, as shown in Fig. 1 of the drawings, there being a pair of these at the back arranged and secured in a manner similar to those shown in said figure at the front of the person. The saddle may also be secured to the vest, if desired, over the shoulder.

The fore and upper arms may be constructed of any suitable, light material, common to structures of this class and the forearm is preferably hollow from end to end, and it is cut away on one side as at 17. The lower end of the upper arm 11 projects into the end of the forearm and these two members are pivotally united as by a pivot 18 secured in the member 11 with its ends projecting beyond the sides of said member and entering supporting straps 19 and 48 secured to opposite sides of the forearm and projecting beyond its upper end, said straps having a swinging movement on said pivot.

The forearm is balanced, so that it may be moved into the position shown in Fig. 4, by the application of little force. In the structure shown herein an abutment 20 extending across the opening in the forearm receives the threaded stem of an adjusting screw 110, the milled edge of the head of which extends through an opening at the back of the forearm. This has a recess 21 to receive the end of a spring case 22, which end is of curved form so that said case may have a rocking movement. A spring 23, preferably of spiral form is seated in this spring case, the latter being open at its upper end, said spring thrusting with its upper end against a shoulder 24 on a plunger 25 that extends into the upper end of the case 22. A stud 26 at the upper end of the plunger 25 projects into a sleeve 27, said sleeve being thus supported by the plunger. A ball 28 on the end of a strut rod 29 is located in the end of the sleeve, said rod projecting through the pivot 18 and being rigidly held thereby to resist the force of the spring 23, and the action of the spring 110

thus tends to bend the arm into the position shown in Fig. 4.

Two ways of bending the arm into the position shown in Fig. 4 are contemplated by me, and either one may be used under certain conditions. One mechanism for effecting this bending operation comprises a bending cord 30 secured inside of the forearm at the back thereof and extending upwardly through the cut-away part 17, into the front of the lower end of the upper arm, through this end of the upper arm and out through the back thereof where it is attached to an anchoring strap 31 extending up over the shoulder and preferably secured to the front of the vest 10 as shown in Fig. 1 of the drawings.

By this arrangement a movement of the stump 13, either straight down or forward, will cause the cord 30 to pull upon the forearm and swing it into the position shown in Fig. 4.

As another means of bending the arm I provide a spring actuating member 32 secured to the front of the upper arm as shown in Fig. 1, and passing around said arm to the opposite side thereof where it is pivotally attached to an arm bending lever 33 that is a bell crank lever pivotally mounted on the outside of the upper arm, the opposite end of said lever being connected by a strut rod 34 with a projection from the upper end of the strap 19 as shown in Fig. 2 of the drawings. The actuating member 32 is provided with a pad 35 adapted to be pressed against the side of the body underneath the arm and as illustrated in Fig. 1. It will be seen from this construction that by pressing the arm stump against the side of the person the upper end of the lever 33 will be pressed forward and its opposite end downwardly, and, acting upon the projection from the strap 19, the forearm will be swung upwardly to the position shown in Fig. 4, the balance of this arm, as hereinbefore described, enabling this action to be readily effected. This means of bending the arm may be employed in instances where the upper arm member is located against the side of the person but when said upper arm member may be raised then the other means hereinbefore described may be employed to effect bending action of the arm, as to cause the hand to reach the head.

55 The opening in the lower end of the forearm 12 is closed by a socket piece 36 that opens to the interior of the arm, this socket piece being secured in place in any desired manner. A shaft 37, preferably hollow, is mounted in the socket piece and projects beyond the lower end thereof and out of the forearm, the opposite end of the shaft having a bearing in a cover 38 secured within the socket piece and closing one end thereof. 60 A coupling collar 39 is rotatably and slid-

ably mounted on the shaft 37, this collar having two grooves, one of which receives the forked arms of a coupling lever 40, the end of said lever opposite its fork projecting through the side of the socket piece. 70 This lever is pivotally mounted in the socket piece, as shown in Fig. 5 of the drawings, and its outer end lies in the path of movement of wrist movement controlling teeth 41 of a ratchet wheel 42 loosely mounted on a stud 43 secured to and projecting from the side of the socket piece and through a hole in the lower end of the forearm. A coupling arm 44 is also pivotally supported on the stud 43, and carries a pawl 45, a coupling cord 46 being secured to said arm. This cord passes upwardly in contact with a guide sheave 47 rotatably mounted on that end of the pivot 18 that receives a supporting strap 48 secured to the forearm 12 on the opposite side from the strap 19 and serving a purpose similar to that of the strap 19. Above the sheave 47 the cord 46 passes through a suitable guide at the upper end of the upper arm 11 and on the side thereof toward the body, said cord passing under the actuating member 32 and being secured to an anchoring strap 49 secured to the vest 10 and extending preferably across the front of the vest and over the opposite shoulder 95 from that supporting the arm, said strap being preferably secured just behind said shoulder.

The crowns of the teeth 41 have retaining notches 50 to receive and retain the coupler lever 40 in its coupling and unlocking position, these notches being so formed that the teeth may be disengaged from the lever on the application of sufficient force applied to rotate the ratchet wheel. The ratchet teeth 51 on the ratchet wheel are so spaced with relation to the wrist movement controlling teeth that little lost movement of the pawl and arm 44 will take place in the swinging movement of the arm to cause step by step movement of the ratchet wheel.

50 A coupler 52 is pivotally mounted in the upper end of the shaft 37, its outer end being adapted to engage locking notches 53 in a locking ring 54 secured to the inner wall 115 of the socket piece 36. These locking notches are located to hold the hand in different positions into which it may be turned in its pivotal movement at the wrist. The coupling collar 39 has a coupling notch 55 in its upper edge adapted to receive said coupler.

An actuator for turning the hand, in the form herein shown consisting of a cord 56, has its ends secured in a groove in the collar 39, the branches of this cord extending out through eyes 57 in the lower arm section, (see Fig. 2) the loop of this cord extending around a guide sheave 58 rotatably mounted on the lower arm member. The 130

coupling arm 44 is held in a normal position of rest by means of an arm returning spring 59 secured to an extension from the arm 44 on the opposite side of its pivot from that at which the cord 46 is attached. A hand turning bar 60 is secured to one of the branches of the loop of the actuator 56, and, as shown in Fig. 2 of the drawings, the outer end of this bar is rigidly attached 10 to a hand turning rod 61 pivotally connected at its upper end to a rod support 62 located at the upper end of the strap 19.

From the above construction it will be noted that when the coupling cord 46 is drawn upon, the arm 44 will be swung on the stud 43 and against the tension of the arm returning spring 59, this movement through the action of the pawl 45 rotating the ratchet wheel 42 and carrying the bevelled portions of the wrist movement controlling teeth 41 against the coupling lever 40, swinging it on its pivot and moving its forked end to carry the coupling collar 39 against the coupler 52, moving the latter 25 from locked engagement with the locking ring 54.

This pull upon the cord 46 is obtained by raising the shoulder on the opposite side of the body from that to which the artificial arm is attached or by moving the stump of the arm away from the body, and the ratchet wheel being consequently turned, as hereinbefore described, a retaining notch 50 on a controlling tooth 41 will be moved under 30 the lever 40 that will drop into said notch and thus be held in its unlocking and coupling position. A bending of the arm, which may be effected as hereinabove described, either by the operation of the bending cord 30 or the actuating member 32, will cause the bar 60 to be moved downwardly on the forearm, owing to the location of the pivot of the rod 61 upon a different center from that on which the forearm turns and a consequent opposition to upward movement of 45 said bar by said rod, and the actuator 56 will operate to turn the collar 39 in the direction indicated by the arrow in Fig. 9. This movement will carry the coupling notch 55 in the collar underneath the coupler 52 that will drop into the notch thus locking the parts together, but the coupler will not drop low enough to again engage the locking notches 53, as the holding of the lever 40 by the teeth 41 will retain the coupler above 55 the ring 54. This movement to lock the parts together will take place during the first part of the bending movement of the arm, and during the rest of such bending 60 movement the continued rotation of the collar 39 will cause the hand to turn as for the purpose of carrying a spoon held in the fingers to the mouth. If a glass of water be held in the hand this turning movement 65 should be avoided, and the unlocking opera-

tion above described will not be effected. If it be desired to retain the hand in the position to which it has been turned as above described and as illustrated in Figs. 4 and 5, a second upward movement of the shoulder or movement of the stump away from the body and a consequent pull upon the cord 46 will force the tooth 41 supporting the lever 40 from engagement with said lever, and its end will drop into the deep 75 spaces between the teeth, thus placing the lever in its locking and uncoupling position, and as shown in Fig. 5 of the drawings.

From the above description it will be seen that the same movement of the body is made 80 use of to effect the locking and unlocking of the wrist movement.

The wrist mechanism above described includes a wrist piece 63 having a circular shaped recess 64 and projecting bearings 65, 85 the latter to receive a pivot bolt 66 that passes through said bearings, through the shaft 37 and through the base of the hand 67, the bolt being secured as by means of a nut, as shown in Fig. 5 of the drawings. 90 The end of this hand is formed on the arc of a circle struck from the center of the pivot bolt 66 as is also the recess 64, and this end of the hand has recesses 68 to receive the projections 65. A thumb 69 is pivotally attached to the hand in any suitable manner, and is forced normally inward as by means of a spring. The hand has a recess 70 to receive a frame that is secured therein in any suitable manner. This frame 100 comprises side parts 71 and a bottom plate 72. Sockets 73 are secured to the side parts and receive plungers 74 that are seated on springs 75 in the sockets. These plungers are joined by a finger actuating bar 76 that 105 is operated by mechanism as follows:

A carrier plate 77 is pivotally supported at one end on the bottom plate 72 and carries a retaining slide 78 having a retaining finger 79 positioned to engage openings in a locking plate 80 secured to the bottom plate 72. A retaining stud 81 projects from the slide 78 in position to engage retaining notches in the holding teeth 82 of a ratchet wheel 83 rotatably mounted on a stud 84 115 secured in the carrier plate 77. A lock actuating lever 85 is pivotally mounted on the pin 86 that pivotally supports the plate 77, and a pawl 87 is pivotally mounted on the lever 85 with its toothed end positioned 120 to engage the teeth of the ratchet wheel. The lever 85 has a bar 88 extending underneath the plate 77 and joined to the main part of the plate by a screw 89 to which an actuating cord 90 is secured. A spring 91 125 forces the lever 85 in a direction opposite to that in which it may be moved by the cord 90, and a spring 92 forces the slide 78 toward the locking plate 80 to engage the finger 79 with the openings in said plate. The 130

bar 76 is composed of a number of sections, three as shown in the drawings herein, and they are united by a rod 93 passing through said fingers and through finger base actuating rods 94. The stud 84 is formed integral with a supporting plate 95 that is extended upwardly and has an overturned lip 96 to receive a supporting ear from a tie bar 97 secured to the actuating bar 76, a screw 98 securing the parts together.

Each of the fingers consists of a base 99 pivotally attached to the hand and a tip 100 pivotally attached to the base. The little finger is supported on a pivot 101, while the first, second and third fingers are supported on a pivot 102 for the three. An actuating rod 94 extends from the bar 76 to each of the fingers. Each rod is connected with one end of a finger tip actuating lever 103, the opposite end of said lever being connected with the finger base 99. A finger tip actuating rod 105 pivotally connects each lever 103 with a finger tip 100.

The actuating cord 90 extends from the lever 85 through the hand and diagonally out through an opening in the wrist piece 63 to the back of the hand and along the forearm and through a guide 107 on the upper arm and to an anchoring strap 108 secured to the vest 10 preferably on the shoulder.

The fingers are closed by a pull upon the cord 90 which may be effected by lowering the shoulder of the stump to which the arm is attached. The arm will thus be extended away from the anchoring strap 108 and the actuating lever 85 will receive the force of this pull. The spring 91 is stronger than the springs 75, with a result that a pull upon the cord 90 will swing the carrier plate 77 and cause it to operate the entire finger mechanism to close the fingers in a manner that will be readily understood. As soon as opposition to closing movement of the fingers takes place, as by an object within the hand, or a closing of the fingers together, swinging movement of the plate 77 will stop and the spring 91 will then give to permit movement of the actuating lever 85, and the latter, through the action of the pawl 87 will rotate the ratchet 83 on its pivot. This operation, if the slide 78 is in its locked position, will, by the action of the cams on the teeth 82, move the slide to its unlocked position, and if the slide is in its unlocked position, the holding notch in the tooth 82 will be forced from engagement with the stud on the slide that will then be permitted to move to its locked position under force of the spring 92. It will thus be seen that the fingers may be caused to grasp an object, after which a continuous pull on the cord 90 will cause the fingers to be locked in this position and the hand and arm may then be operated as hereinbefore described. When it is desired to loosen the fingers from the

grasp of the object, the cord 90 is pulled in the same manner as before, and it thus becomes apparent that both the locking and unlocking movements take place by the same action of the cord 90.

The pawl 87 is held normally in engagement with the teeth of the ratchet wheel by means of a spring 111 secured to the pawl and to a screw in the end of the stud 84. The bar 88 is formed from a portion of the lever 82 bent into proper form, the bent portion forming a stop 109 to limit the movement of the lever 85 with respect to the plate 77. The hand may be bent, by a movement on the pivot 66, by forcing it into various positions, and the friction between the parts will be sufficient to retain the hand in any such position to which it may have been moved.

The hand may be swung to a position with its back toward the front, which will be necessary for some purposes, and in such case, if the hand is locked in this position, the coupler 52 will be swung in a direction opposite to that indicated by the arrow in Fig. 9 and to engage the notch at the top of said figure. This result may be attained by bending the arm until the coupler 52 is unlocked from the notch 53, the arm being only partially bent to effect this purpose. This movement will carry the coupling notch 55 into locked engagement with the coupler, and now lowering the forearm, the coupling collar will move the shaft 37 and consequently the hand in a reverse direction to that indicated by the arrow in Fig. 9. The hand may be locked in this position by operating the mechanism as hereinbefore described, and it may be unlocked and carried to the position shown in Figs. 1 and 2, and locked and unlocked in this position, or it may be turned to the position shown in Figs. 4 and 5 and locked or unlocked in this position. This turning movement is a swivel movement of the hand with respect to the forearm that is obtained by means of the turning movement of the shaft to which the hand is secured.

I claim—

1. An artificial limb including an upper arm and a forearm pivotally attached thereto, an actuating member movably secured to the upper arm and located to receive pressure between said upper arm and the body of the wearer for actuation of said member, and a connection between said actuating member and forearm to effect bending movement of the latter.

2. An artificial limb including an upper arm and a forearm pivotally attached thereto, an actuating member partially encircling and movably supported by the upper arm and extending between said arm and the body to receive pressure therebetween, and a connection between said actuating member

and forearm to effect bending movement of the latter by reason of such pressure.

3. An artificial limb including an upper arm and a forearm pivotally attached thereto, an actuating member movably secured to the inside of the upper arm to be actuated by pressure against the body, a bending lever pivotally attached to the upper arm, an operative connection between the bending lever and said actuating member, a strap secured to the forearm and projecting above its upper end, and a strut rod pivotally attached to said bending lever and to said projecting strap to effect bending movement of the fore- 15 arm.

4. An artificial limb including an upper arm and a forearm pivotally attached thereto, a hand having a swivel connection to the lower end of the forearm to turn on the longitudinal axis thereof, an actuator movably mounted on the forearm and operatively connected with the hand to turn it on said longitudinal axis, and a connection between said actuator and the upper arm to 25 effect movement of the actuator as the arm is bent.

5. An artificial limb including an upper arm and a forearm pivotally attached thereto, a hand having a swivel connection to the lower end of the forearm to turn on the longitudinal axis thereof, an actuator movably mounted on the forearm and operatively connected with the hand to turn it on said longitudinal axis, and a connection 35 extending from the actuator and pivotally connected to the upper arm at a point removed from the axis of the forearm in its turning movement on the upper arm.

6. An artificial limb including an upper arm, a forearm pivotally attached thereto and having an abutment, a spring case seated against said abutment, a spring inclosed in said case to thrust it against said abutment, and a strut rod secured to the upper arm 45 and connected with the spring to resist expanding movement thereof whereby expansion of the spring assists in bending movement of the forearm.

7. An artificial limb including an upper arm, a forearm pivotally attached thereto, and a spring positioned and arranged to exert thrust between said upper and forearms in a direction to influence bending movement of the latter.

8. An artificial limb including an upper arm, a forearm pivotally attached thereto, a strut rod secured to the upper arm, an abutment in the forearm, a spring casing supported by said abutment, a spring within said casing, and a connection between said spring and strut rod whereby said rod resists said expanding movement of the spring.

9. An artificial limb including an upper member, a forearm pivotally attached thereto, a hand swivelly attached to the forearm

to turn on the longitudinal axis thereof, means for locking the hand in different positions, an actuating member for bending the arm, an actuating member for turning the hand, and an actuating member for the locking mechanism, all extending to and connected with the upper arm. 70

10. An artificial limb including an upper arm, a forearm pivotally attached thereto, a hand swivelly attached to the forearm, fingers movably attached to the hand, mechanism for locking the hand against movement, actuating members connected one to the finger moving mechanism, and one to the hand locking mechanism and extending and 75 secured to a vest, and a vest adapted to be secured to a person. 80

11. An artificial limb including an upper arm, a forearm pivotally attached thereto, a hand swivelly attached to the forearm to turn on the longitudinal axis thereof, mechanism for turning the hand, mechanism for locking the hand against movement, fingers movably secured to the hand, mechanism for moving the fingers, and actuating members 85 extending one from the forearm to bend it, one from the hand turning mechanism, 90 one from the hand locking mechanism, and one from the finger moving mechanism, all of said actuating members being attached 95 to the upper arm.

12. An artificial limb including a forearm, a hand swivelly attached to the forearm to turn on the longitudinal axis thereof, means for locking the hand in different positions, and an actuating member connected with said locking means and movable in the same manner both to lock and unlock the said locking mechanism. 100

13. An artificial limb including a forearm, a hand swivelly attached to the forearm, a lock to lock the hand in different positions, mechanism for operating the lock and including a member movable in the same direction to lock and unlock the arm, 105 and a cord connected with said member and operating by a pull to cause both locking and unlocking action of said mechanism.

14. An artificial limb including a forearm, a hand swivelly attached to said forearm, a lock to lock the hand in different positions, a member rotatably mounted for step by step movement to move the lock to locking and unlocking positions, and means for effecting step by step movement of said 115 rotating member.

15. An artificial limb including a forearm, a hand swivelly attached thereto on an axis extending longitudinally of the forearm, mechanism for turning the hand on 120 said axis, mechanism for locking the hand in different positions to which it may be turned on said axis, means for connecting and disconnecting said locking and turning mechanism, and means for actuating each 125 130

- of said mechanisms to retain the hand in different positions to which it may be turned.
16. An artificial limb including an upper member, a forearm pivotally attached to the upper member, a hand swivelly attached to the forearm on an axis extending longitudinally of the forearm, mechanism for turning the hand on said axis, a connection between said turning mechanism and the upper arm to actuate said mechanism when the arm is bent, a locking mechanism, means to connect said locking mechanism and said turning mechanism, and means to operate said lock.
17. An artificial limb including a forearm, a hand swivelly attached thereto, mechanism for locking the hand in different positions, mechanism for turning the hand, means to couple the locking mechanism with the turning mechanism, and a member having a step by step movement always in one direction to operate said lock for locking and unlocking action, and means for operating said member.
18. An artificial limb including a forearm, a shaft rotatably mounted in said arm, a hand secured to said shaft, means for rotating said shaft and including a sliding collar, means for actuating said collar, means including a coupler for locking the hand in different positions, said coupler being located in the path of movement of said collar to be actuated thereby, and means for actuating the collar.
19. An artificial limb including a forearm, a shaft rotatably mounted in the forearm, a hand secured to said shaft, a coupler pivotally mounted in the shaft, a collar slidably mounted on the shaft to actuate said coupler and having means to receive the coupler for coupling action, means engaged by the coupler for locking action, and means for actuating the collar.
20. An artificial limb including a forearm, a shaft rotatably mounted in said arm, a hand secured to said shaft, a coupler pivotally secured to said shaft, a locking ring having notches to receive said coupler, a sliding collar having a notch to receive said coupler, and means for operating the collar.
21. An artificial limb including a forearm, a shaft rotatably mounted in said arm, a hand secured to said shaft, means for locking the shaft with the hand in different positions, means movable on the shaft to operate said lock, and means engaging the lock operating means to effect turning movement of the hand.
22. An artificial limb including a forearm, a shaft rotatably mounted in said arm, a hand secured to said shaft, a locking member secured to said shaft to lock the hand in different positions, a collar slidably mounted on the shaft to operate said lock, means extending around the collar to effect turn-
- ing movement of the hand, and means for operating the collar.
23. An artificial limb including a forearm, a hand swivelly attached to said arm, a coupler pivotally mounted and rotatable with said hand, a sliding collar having a notch to receive said coupler, means to operate the collar, and means to engage the coupler to lock the hand against turning movement.
24. An artificial limb including a forearm, a shaft rotatably mounted therein, a hand secured to said shaft, a coupler pivotally mounted in the shaft, means to engage said coupler for locking action thereof, a collar slidably mounted in the shaft to operate said coupler for locking and unlocking action, said collar having a groove to receive said coupler for coupling action, an actuating cord extending around said collar to effect turning movement thereof, and means for actuating the collar.
25. An artificial limb including a forearm, a socket piece secured in the lower end of said arm, a shaft rotatably mounted in said socket piece, a hand secured to said shaft, a locking ring located inside of the socket piece and having notches, a coupler pivotally mounted in the shaft to engage said locking notches, a collar slidably mounted on said shaft to operate said coupler and having a notch to be engaged by the coupler for coupling action, a cord extending around said collar to the outside of the arm, means connected with the cord to effect rotation of said collar, and means for operating the collar for locking and unlocking action.
26. An artificial limb including a forearm, a hand swivelly mounted on said arm to turn on an axis extending longitudinally of the arm, means for turning the hand, mechanism for locking the hand in different positions and including a lever, a rotating member to actuate said lever for locking and unlocking movements, and means for imparting a step by step movement to said rotating member.
27. An artificial limb including a forearm, a hand swivelly attached thereto, means for turning the hand, mechanism for locking the hand in different positions, and lock operating mechanism including a lever, a toothed member to operate said lever and having notches at the crowns of the teeth to engage and hold said lever in unlocked position, and means for imparting a step by step movement to said toothed member.
28. An artificial limb including a forearm, a hand swivelly attached thereto, means for turning the hand, mechanism for locking the hand in different positions and including a lever, a member rotatably mounted and having teeth with notches in the crowns to receive and hold said lever in

unlocked position, a coupling arm mounted for reciprocating movement and operatively connected with said rotatable member, and means for actuating said arm.

29. An artificial limb including a forearm, a hand swivelly attached thereto, mechanism for turning the hand, mechanism for locking the hand in different positions and including a lever, a toothed member rotatably mounted and having notches to engage said lever to hold it in unlocked position, a ratchet wheel attached to said toothed member, a coupling arm having a pawl to engage said ratchet, and means for operating said coupling arm.

30. An artificial limb including a forearm, a hand swivelly attached thereto, means for turning the hand, mechanism for locking the hand in different positions and including a lever, a toothed member having a set of notches to engage and hold said lever in unlocked and coupled position and also a set of notches to hold said lever in uncoupled and locked position, and means for imparting a step by step movement to said toothed member always in the one direction.

31. A hand having fingers attached thereto for bending movement, a carrier plate connected with the fingers to move them in one direction, springs to return the plate in the opposite direction, an actuating lever pivotally mounted, a spring connection between said plate and lever stiffer than the springs for effecting said returning movement of the fingers, and means for actuating said lever.

32. A hand having fingers attached thereto for bending movement, a frame secured within a recess in the hand, a bar slidably mounted and operatively connected with said fingers, plungers attached to said bar, springs upon which said plungers are seated, a pivotally mounted carrier plate operatively connected with said bar, an actuating

lever having a movement independent of said plate, means for connecting the lever with said plate after the lever has effected part of its movement, said connecting means including a spring stiffer than the springs upon which said plungers are seated, and means for operating said lever.

33. A hand having fingers attached thereto for bending movement, and having a recess, a frame located in said recess, a bar slidably mounted in said frame, plungers supporting said bar, springs upon which said plungers are mounted, a carrier plate operatively connected with said bar, an actuating lever having a movement independent of said plate, a spring connecting said lever and said plate and stiffer than springs supporting said plungers, means for actuating said lever, means for connecting said lever with the slide after the lever has effected part of its movement, and a locking bolt operatively connected with the actuating member to be operated thereby.

34. An artificial limb including an upper arm, a forearm pivotally attached thereto, an actuating member movably secured to the upper arm and located to receive pressure between said upper arm and the body of the wearer for actuation of said member, a connection between said actuating member and forearm to effect bending movement of the latter, and a second means for effecting bending movement of said forearm.

35. An artificial limb including a forearm, a hand swivelly mounted on said forearm to turn on the longitudinal axis thereof, means for turning the hand in one direction, mechanism for locking the hand in different positions and including a lever, a rotatable member to actuate said lever for locking and unlocking movements, means for turning the hand in an opposite direction for effecting unlocking movement, and means for actuating said rotatable member.

OTTO LE GRAND DILWORTH.
